UNITED STATES PATENT OFFICE.

ALVIN AMOS CROSSMAN, OF VERNON, TEXAS.

PIPE AND LIKE STEM.

1,369,624.

Specification of Letters Patent. Patented Feb. 22, 1921.

Application filed April 15, 1920. Serial No. 374,148.

To all whom it may concern:

Be it known that I, ALVIN AMOS CROSSMAN, a citizen of the United States, residing at Vernon, in the county of Wilbarger and 5 State of Texas, have invented certain new and useful Improvements in Pipe and Like Stems; and I do declare the following to be a full, clear, and exact description of the invention, such as will enable others skilled in 10 the art to which it appertains to make and use the same.

My invention relates to smoking equipment and more particularly to stems such as those used on pipes, cigarette holders and 15 cigar holders; and my principal object is to provide a stem of such construction as to prevent saliva from running down the bore of the stem, thus overcoming a number of well known disadvantages and difficulties 20 heretofore encountered.

With the foregoing in view, the invention resides in the novel stem hereinafter described and claimed, the descriptive matter being supplemented by the accompanying 25 drawings.

Figures 1 and 2 are side elevations partly in section, showing the application of my invention to both straight and curved stem pipes.

30 Fig. 3 is a longitudinal section of a cigarette holder constructed in accordance with my invention.

Fig. 4 is a sectional view of a cigar holder embodying the improved details of construction.

Fig. 5 is a sectional perspective view of the rear end of one of the stems.

In the drawings above briefly described, the numeral 1 designates a one-piece stem 40 constructed in accordance with my invention, and such stem may be used on numerous forms of pipes, or as cigarette and cigar holders. In all cases, the rear end of the stem is provided on its upper side with an 45 integral, preferably rounded, projection 2

whose front side is provided at a point contiguous to the stem, with a transverse slot 3 or other suitable opening. The bore 4 of the stem 1 turns upwardly at its rear end as seen at 5, within the rear portion of the projection 2 and then turns forwardly and downwardly as indicated at 6, opening into the slot or the like 3. By this formation, it is impossible for any saliva to run down the bore 4 and come in contact with the tobacco.

From the foregoing, it will be obvious that although my invention is of extremely simple and inexpensive nature, it will be highly efficient and in every way desirable, 50 particular emphasis being laid upon the fact that the projection 2 not only permits formation of the bore in the required manner, but serves to abut the user's teeth so that the stem is prevented from sliding from the 55 mouth. Since probably the best results may be obtained from the exact structure shown, such structure is preferred, but within the 60 scope of the invention as claimed, minor 65 changes may of course be made.

I claim:

1. A smoking stem having a projection extending upwardly from its rear end, said stem having a longitudinal bore whose rear end extends upwardly into said projection 70 and then turns forwardly and downwardly, opening through said projection at a point adjacent the upper side of the stem.

2. A smoking stem having an integral enlargement extending upwardly from its 75 rear end and provided at a point adjacent said stem with a transverse slot, said stem having a longitudinal bore whose rear end extends upwardly into said projection and then extends forwardly and downwardly, 80 opening into said slot.

In testimony whereof I have hereunto set my hand.

ALVIN AMOS CROSSMAN.
